CLAIM

The ornamental design for a joint device for cable racks, as shown and described.

DESCRIPTION

FIG. 1 is a perspective top elevational view illustrating a first embodiment of my new design for a joint device for cable racks;

FIG. 2 is a perspective bottom elevational view of the joint device for cable racks of FIG. 1;

FIG. 3 is a left side view of the joint device for cable racks of FIG. 1;

FIG. 4 is a right side view of the joint device for cable racks of FIG. 1;

FIG. 5 is a top plan view of the joint device for cable racks of FIG. 1;

FIG. 6 is a bottom plan view of the joint device for cable racks of FIG. 1;

FIG. 7 is a front plan view of the joint device for cable racks of FIG. 1;

FIG. 8 is a rear plan view of the joint device for cable racks of FIG. 1;

FIG. 9 is a perspective elevational view illustrating a second embodiment of my new design for a joint device for cable racks;

FIG. 10 is a right side view of the joint device for cable racks of FIG. 9;

FIG. 11 is a left side view of the joint device for cable racks of FIG. 9;

FIG. 12 is a top plan view of the joint device for cable racks of FIG. 9;

FIG. 13 is a bottom plan view of the joint device for cable racks of FIG. 9;

FIG. 14 is a rear plan view of the joint device for cable racks of FIG. 9; and,

FIG. 15 is a front plan view of the joint device for cable racks of FIG. 9.
